(57) **CLAIM**

The ornamental design for a spray bottle, as shown and described.

DESCRIPTION

FIG. 1 is a perspective view of a spray bottle, showing the top, a side and the front of our new design;

FIG. 2 is a front elevational view of the spray bottle;

FIG. 3 is a back elevational view of the spray bottle;

FIG. 4 is a right side elevational view of the spray bottle;

FIG. 5 is a left side elevational view of the spray bottle;

FIG. 6 is a top plan view of the spray bottle;

FIG. 7 is a bottom plan view of the spray bottle; and,

FIG. 8 is a perspective view of the spray bottle as in FIG. 1, further having an attached overcap shown in broken lines; the overcap is shown only for illustrative purposes and forms no part of the claimed design.

In all of the figures, the spray nozzle is not required to be oriented in the direction depicted, as it is freely rotatable independently of the bottle portion.
